DISPENSER

William H. Carr, Jr., Kansas City, Mo.

Application December 19, 1949, Serial No. 133,821

2 Claims. (Cl. 242—55.5)

1

This invention relates to a device for dispensing desired lengths of metal foil or other sheet material, such as wax paper.

An object of the invention is the provision of a dispensing device in the form of an elongated casing supporting a roll of metal foil therein, the front wall of said casing being provided with a pair of elastic jaws which are compressed upon a width of the foil when a hinged closure is pressed into place so that the foil on the roll will be retained against shifting movement when a section of the roll withdrawn from the casing is being torn off against a cutter carried by the closure.

Another object of the invention is the provision of a device for dispensing desired sections from a roll of metal foil or the like in which the free end of the material is clamped by resilient jaws to prevent breakage or mutilation of the foil at such points when the desired length of foil is being torn or cut off by a shearing means carried by a housing for the roll, the jaws being retained in clamping relation by a lid on a casing which houses the roll.

A further object of the invention is the provision of a device for dispensing desired lengths of a metal foil or the like from a roll in a casing in such a manner that the roll will be held against further dispensing action when a pull is exerted on the foil during severance of the selected section from the roll of foil, said foil being retained against slippage by a pair of spaced jaws formed of rubber and between which the foil is withdrawn from said roll, pressure on the jaws by a movable lid on the casing creating a clamping action on the foil.

This invention is best understood from a consideration of the following detailed description taken in connection with the accompanying drawing forming a part of the specification, nevertheless, it must be borne in mind that the invention is not confined to the disclosure, but is susceptible of such changes and modifications as shall define no material departure from the salient features as expressed in the appended claims.

In the drawings—

Figure 1 is a view in perspective of my dispenser showing one form thereof.

Figure 2 is an enlarged transverse vertical section of a modified form of the dispenser, showing the lid or closure in open position.

Figure 3 is an enlarged transverse vertical section of the form shown in Figure 2 with the lid closed and with the device in condition for dispensing.

5

Figure 4 is a greatly enlarged fragmentary vertical section of a holder for a clamping means, and

Figure 5 is a greatly enlarged fragmentary vertical section of a modified form of the clamping means shown in Figure 4 disclosing also a modified form of the closure.

Referring more particularly to Figure 1, it will be seen that a casing 10, rectangular in cross section provides a housing for a roll 11 of metal foil 12 which is cut-off in desired lengths for a purpose presently to be described. A spindle 13 upon which the foil is wound has the opposite ends received by bearings 14 formed in the end walls 15 of the casing. The casing includes a front wall 16, a rear wall 17 and a bottom 18.

A lid 20 forms a closure for the upper open portion of the casing and is hinged at 21 on the upper edge of the rear wall 17. The front edge of the lid extends beyond the front wall 16 for the entire length of said lid. A downturned flange 23 which terminates short of the length of the lid depends from the front free edge 22. A horizontal flange 24 formed integrally with the flange 23 projects forwardly from the lower edge of said flange. The free edge of the flange 24 is provided with a plurality of spaced cutting or saw teeth 25 for shearing off a predetermined length of the foil.

30 A clamping means 26 for retaining the foil on the roll 11 against slippage when a projecting portion of said foil is being sheared off, is mounted on the upper edge of the front wall 16. This clamping means consists of a flat strip of rubber and has its lower edge secured to the upper edge of the front wall. The ends of the strip are secured to front upper portions of the end walls 15. The strip has an elongated horizontal slot 27 through which the foil from the roll 11 is threaded. It will be noted that the upper edge of the front wall 16 falls short of the height of the end walls 15. When the clamping member 26 is secured in place on the top edge of the front wall 16, the top edge of the upper jaw 28 of the clamping member will be located above the top edges of the end walls 15 so that when the lid 20 is lowered onto the jaw 28 and pressed downwardly, said jaw will clamp the foil against a jaw 29 of the clamping means.

35 In Figures 2 to 4 inclusive, there is illustrated a modified form of a holder or support for the clamping means 26a. In this form, the upper edge 30 of the front wall 16a is bent inwardly and then downwardly as shown at 31 and thence upwardly at 32 to provide a transversely curved and elongated channel member to receive the

lower edge of the clamping means 26a or the jaw 29a which is spaced from and below the jaw 28a. The elongated slot 27a between the jaws is adapted to receive the metal foil 12 as shown more particularly in Figure 3. The upper edge of the jaw 28a projects above a horizontal plane passing through the upper edges of the end walls 15 for a purpose which will be explained presently.

The operation of my dispensing device illustrated in Figures 1 to 4 inclusive is as follows:

The ends of the spindle 13 are placed in the bearings 14 supporting the roll 11 of metal foil 12. The free end of the foil is threaded through the slot 27 in the clamping means 26 (Figure 1) or the slot 27a in the clamping means 26a (Figures 2 to 4 inclusive). A sufficient length of the foil is withdrawn through the slot from the roll and the lid or closure 20 is pressed downwardly on the top jaw 28 or 28a, whereby the foil is clamped against slippage between the jaws. It will be noted that the jaw 28 or 28a extends above the top edges of the end walls 15 and since the jaws 28 and 29 or 28a and 29a are formed of elastic materials, the pressure on the lid 20 will compress the jaws firmly against the foil to hold said foil in position when the projected section is sheared-off against the teeth 25 on the horizontal flange 24.

Referring to Figure 5, a modified form of the dispensing means is shown. In this form, the front wall 35 has an enlarged upper edge 36 provided with a longitudinal groove 37. It is to be borne in mind that only the lid 20a and the front wall 35 of the housing, as illustrated in Figure 1 is disclosed. An elongated jaw 38 is fixed in the groove 37 and has its upper free edge throughout the length thereof adapted to contact and support the metal foil 12.

The lid 20a has an enlarged free edge 40 with a flat under surface 41. Shearing teeth 42 project forwardly from the reduced edge 43 of the enlarged portion of the front edge of the lid. The enlarged free edge 40 of the lid has a longitudinal groove 44 in which is fixed the upper jaw 45. In this form, the jaws are independent of each other, so that when the lid 20a is raised, the jaw 45 will be raised, while the jaw 38 remains in place in the enlargement 36 at the upper edge of the front wall 35 of the housing or casing for the roll 11 of the foil. No threading is required in the modification illustrated in Figure 5.

The foil 12 may be torn-off from the roll 11 in any suitable lengths. The lengths of the foil may be employed for wrapping various kinds of foods before storing such foods in a refrigerator to prevent the odors of such foods from affecting the flavors of other foods. The sections of the foil may also be employed in various cooking

processes. The foil is manufactured preferably from aluminum, since such foil will not corrode or melt except at extremely high temperatures.

While I have particularly defined the severance of metal foil, it should be understood that a roll of wax paper can be employed in the device with equal effectiveness in shearing a desired length of such paper.

I claim:

1. A dispenser for metal foil or the like comprising a casing adapted to house a roll of foil and having a front wall, a rear wall and parallel end walls, a lid having one longitudinal edge hinged to the upper edge of the rear wall with the opposite free edge of said lid being provided with a cutting edge projecting outwardly from the upper edge of the front wall, the front wall having less height than the rear and end walls, said upper edge of the front wall having an integrally formed longitudinal channel member at the inner face of said wall, a flat strip of elastic material having the lower longitudinal edge fixed in said channel member and provided with a longitudinal slot to receive the free end of the foil for dispensing purposes, said slot dividing the strip into a pair of compressible jaws, one of the jaws projecting above a plane passing through the upper edges of the rear and end walls so that when the lid is pressed downwardly on the strip the jaws will clamp the foil against slippage.
2. A dispenser for metal foil or the like comprising a casing adapted to house a roll of foil and having a front wall, a rear wall and parallel end walls, a lid having one longitudinal edge hinged to the upper edge of the rear wall with the opposite free edge of said lid being provided with a cutting edge projecting outwardly from the upper edge of the front wall, the front wall having less height than the rear and end walls, a pair of spaced elastic jaws mounted upon the front wall extending longitudinally and projecting above the upper edge thereof, adapted to receive the free end of the foil therebetween and to be clamped onto the foil when the free end of the lid is pressed into closed position to prevent slippage of the foil when a projecting portion of the foil is sheared off by the cutting edge.
